United States Patent Office.

M. V. BRIGHAM, OF MANNSVILLE, NEW YORK.

Letters Patent No. 94,180, dated August 31, 1869.

IMPROVEMENT IN REEL AND SWIFT.

The Schedule referred to in these Letters Patent and making part of the same.

To all whom it may concern:

Be it known that I, M. V. BRIGHAM, of Mannsville, in the county of Jefferson, and in the State of New York, have invented certain new and useful Improvements in Quill-Wheels, Swifts, &c.; and do hereby declare that the following is a full, clear, and exact description thereof, reference being had to the accompanying drawing, making a part of this specification, in which—

Figure 1 is a side elevation of my improvement, and

Figure 2 is a front elevation of the same.

Letters of like name and kind refer to like parts in each of the figures.

My invention consists in the peculiar construction and arrangement of a quill-wheel, swift, and reel, by means of which the several devices are adapted to each other, and so combined as to occupy the same space only that has heretofore been required for each, whereby their cost is materially lessened, and greater convenience secured.

In the annexed drawing—

A represents the bed-piece, supported upon suitable legs, B B, and consisting of two parts, *a* and *a'*, the former of which is provided, upon each side, with a tongue, which fits into a corresponding groove in the latter, so as to permit said parts to be shut together or drawn out, and shorten or lengthen said bed.

A hand-screw, C, is journalled within a short vertical standard, D, secured to the part *a*, and passes through a corresponding nut, E, attached to the part *a'*, by which means, when said screw is turned to the right or left, said parts *a* and *a'* are adjusted to or from each other.

Secured to and extending upward vertically from the outer end of the bed-piece, is a standard, F, in the upper end of which is journalled a horizontal shaft, G, having upon one end a screw-thread, *g*, and upon the other a grooved wheel, H.

Journalled within the standard F and a brace, *f*, below and parallel with the shaft G, is a spindle-shaft, I, having upon its inner end, between said standard and brace, a grooved pulley, K.

A cord, *k*, passes around both wheel and pulley, so that when said wheel is revolved, motion is communicated to said pulley and spindle, the whole, as thus constructed, forming the quill-wheel.

To form the reel, two arms, L L, are secured together in the form of a Greek cross, and, by means of a suitable opening at their centre, are passed over the shaft and against the face of the wheel H.

A pin, *l*, passing through one of the arms and through an arm of the wheel, secures them together, and also furnishes a handle for operating the reel.

Projecting outward from the face of the arms, and at a right angle therewith, are four studs, M M, upon which the yarn is wound. A series of holes in said arms permits of the radial adjustment of the studs so as to conform to the size of the skein desired.

Projecting horizontally to the rear from the standard F, is an arm, N, upon which is pivoted a worm-wheel, O, its axis being at a right angle with the shaft G, so as to permit the teeth of said wheel to engage with the screw-thread upon said shaft.

A pin, *o*, projecting outward from the face of said wheel, engages with a spring, *n*, secured upon the arm N, so that at each revolution of said wheel, said spring is raised and released, producing sufficient sound to warn the operator.

The number of teeth in said wheel being made to correspond with the number of threads desired in each knot of the skein, it will be evident that at each revolution of the same, as indicated by the warning-snap of the spring, the required number of threads will be wound upon the reel.

When it is desired to form a swift, the arms L L are detached from the shaft G, and placed upon the upper end of the standard D, where a suitable bearing or journal, *d*, is provided, in which position said arms form a convenient and desirable means for holding yarn, thread, &c., while being rewound.

In order to accomplish the latter object, a spool or quill is placed upon the spindle of the quill-wheel, and the end of the thread or yarn from the skein upon the swifts secured thereto, when by turning the wheel H, said thread or yarn will be drawn from the swifts and quickly rewound upon the spool.

It will be readily seen that when the device is used as a reel, the bed-piece will require sufficient length only to give it a firm bearing upon the floor; but when used as a swift, said bed-piece will require lengthening, so as to permit the arms L to revolve without striking other portions of the device, and the screw is employed for this purpose.

The especial advantages possessed by this device are, convenience and cheapness, as, from its construction, so little space is occupied as to enable it to be stored as readily as either one of the heretofore separate implements, while, from its compactness and the small number of parts required, it can be furnished at a small cost, as compared with other devices intended for a like purpose.

Having thus fully set forth the nature and merits of my invention,

What I claim as new, and desire to secure by Letters Patent, is—

The within-described device, consisting of the bed-piece A, the screw C, the standard D, provided with

the journal *d*, the nut *E*, the standard *F*, the horizontal shaft *G*, provided with the screw *g*, the grooved wheel *H*, the spindle *I*, provided with the grooved pulley *K*, the arms *L* and *L*, provided with the studs *M*, the arm *N*, the worm-wheel *O*, provided with the stud *o*, and the spring *n*, all constructed and arranged to operate substantially as and for the purpose specified.

In testimony that I claim the foregoing, I have hereunto set my hand and seal, this 18th day of June, 1869.

M. V. BRIGHAM. [L. S.]
